JOSEPH SLEPIAN, OF SWISSVALE, PENNSYLVANIA, ASSIGNEE TO WESTINGHOUSE ELECTRIC & MANUFACTURING COMPANY, A CORPORATION OF PENNSYLVANIA.

X-RAY TUBE.

Application filed April 1, 1922. Serial No. 548,636.

My invention relates to electron-tube devices and particularly to such devices as are adapted to generate X-rays.

An object of my invention is to provide an electron tube having an electron-emitting element and a co-operating element or target, wherein the electrons emitted from said source are caused to attain a velocity greater than that which is given by the influence of any electrostatic potentials impressed upon said elements.

Another object of my invention is to provide an X-ray tube which is capable of producing useful X-rays with relatively low voltages, in comparison to the voltages heretofore considered necessary.

A further object of my invention is to provide an X-ray tube which is simple in design and in construction and which has highly desirable operating characteristics.

Heretofore, in order to produce X-rays having sufficient penetration or hardness to be useful, it has been necessary to employ relatively high voltages, as from 20,000 volts to 100,000 volts, or more. Such X-ray tubes comprise an electron-emitting cathode and a target upon which electrons emitted from the cathode are caused to impinge with extremely high velocity. The maximum velocity with which the electrons strike the target has heretofore been determined solely by the difference in potential between the cathode and the target. Tubes employing potential differences of 100,000 volts or more are now in common use, and the tendency of the art is toward a constantly increasing voltage.

It is obvious that the use of such voltages constitutes a great element of risk, especially when it is necessary to work in confined quarters or to bring the tube close to the body of a patient under treatment.

According to my invention, I cause the electrons which produce the X-rays to attain an extremely high velocity without depending upon the usual direct electrostatic action between the cathode and the target, which, as stated, requires the use of extremely high potentials.

The desired result is obtained by subjecting the electrons to the inductive effects of a varying magnetic field. It is well known that a varying magnetic field has associated therewith an electric field, the

lines of force of which are perpendicular 55 to the lines of force of the varying magnetic field, and it is this electric field which I utilize to impart velocity to the electrons, all as will be explained more fully hereinafter.

With these and other objects in view, my 60 invention further consists in the nature, the mode of operation, the circuit arrangement and the constructional details hereinafter more fully set forth and claimed.

In the drawing, Figure 1 is a diagrammatic representation of circuits and apparatus embodying my invention, shown partially in section;

Fig. 2 is a top plan view of the evacuated container of Fig. 1, illustrating the path 70 taken by the electrons when under the influence of an electrostatic force between the cathode and the target and when under the influence of an additional transverse magnetic field;

Fig. 3 is a view similar to that of Fig. 2, showing the effect upon the electron path of a varying magnetic field;

Fig. 4 is a horizontal sectional view of a structure embodying the preferred form of 80 my device, the section-plane being indicated by the line IV—IV in Fig. 5;

Fig. 5 is a longitudinal section on the line V—V of Fig. 4.

In Fig. 1 is shown a disk-shape electron 85 tube 1 having opposite parallel faces 2 and 3. An electron-emitting element 4, which is energized from a source 5 of direct-current energy, is centrally disposed within the tube 1. An anode or target 6 is disposed 90 adjacent the outer periphery of the tube 1. A conductor 7 serves to connect the anode 6 and the cathode 4 and may include a direct-current source of energy 8, the effect of which is to draw the electrons from the 95 surface of the cathode 4, and thereby give the initial electron loop as large a radius as possible. The advantage of this condition will be explained hereinafter.

A magnetic field, which is transverse to 100 the plane of the tube 1, is obtained by disposing the disk-shaped pole pieces 9 and 11 of a substantially U-shape magnet 12 adjacent opposite faces of the tube 1. The magnet 12 may be excited by means of a 105 magnetizing winding 13, which is wound around a curved portion 14 of the magnet 12 and energized from a source 15 of direct-

current energy. An input or exciting coil 16 is disposed in the plane of the tube 1 immediately adjacent the periphery thereof, and may be excited from a source 17 of 5 alternating current or condenser discharge.

When neither of the magnetizing windings 13 and 16 is excited and a potential difference is established between the electron-emitting element 4 and the anode 6, 10 the electrons emitted from the element 4 are caused to follow the electrostatic lines of force existing between the two elements just mentioned, as indicated by dotted lines *a* in Fig. 2. Here, it will be noted that the 15 velocity of the electrons impinging upon the target 6 is determined solely by the potential difference existing between the cathode 4 and the target 6. As hereinbefore stated, it has been found necessary to resort to 20 potentials of the order of 100,000 volts or more to produce X-rays having useful penetration values.

When the direct-current exciting winding 13 is energized by the energy source 15, a 25 unidirectional magnetic field is produced, which is transverse to the plane of the electron path, and it is found that the current to the anode ceases and that the electrons are caused to move about the cathode 4 in 30 substantially closed paths or loops, as indicated by curved lines *b* of Fig. 2. This has been proved mathematically and is an effect which is well known in the art.

When the alternating-current exciting 35 winding 16 is energized and a varying electric field is produced which lies substantially in the plane of the container 1, the kinetic energy or velocity of the electrons is greatly increased for each complete traversal of its 40 path *b*. The action is not unlike that observed in the ordinary transformer, the exciting winding 16 corresponding to the primary winding of the transformer and the path represented by one complete revolution 45 of an electron as a secondary coil. In the transformer, the potential of the secondary winding increases with the number of turns and the time rate of change of the flux threading the same. Similarly, in my device, the potential energy or velocity of an 50 electron increases with each complete traversal of its path and also with increases in the diameter of its path.

At first hand, it would appear that an 55 electron would continue to revolve in its orbit indefinitely and that the velocity thereof would tend to become infinite in value. However, it may be demonstrated mathematically that the action of the centrifugal 60 forces operating upon the electron are such that it tends to traverse a spiral path of ever increasing radius until it impinges upon the target, as illustrated by the spiral curve *c* of Fig. 3. The exact nature of the spiral

path will be dependent upon the initial velocity of the electrons, which are emitted from the cathode 4, as well as upon the relative values of the constant magnetic field produced by the winding 13 and the alternating magnetic field produced by the wind- 70 75 80 85 90 95 100 105 110 115 120 125

When the electrons finally impinge upon the target 6, their kinetic energy has attained such value that X-rays are produced of a penetrating value equivalent to that of X-rays which could be produced heretofore only by the application of very much higher external potentials between the cathode 4 and the anode 6 when utilizing the influence of the direct electrostatic action alone.

The device of Fig. 1, however, has a serious limitation by reason of the fact that the maximum practically attainable initial radius of the electron loop *b* is relatively small and, hence, alternating currents of extremely large values and of high frequencies must be applied to the exciting coil 16 to produce the desired results hereinbefore stated.

In the preferred form, as shown in Figs. 4 and 5, the cathode 4 and the target 6 are so disposed that the path of the electrons, upon the electrons coming under the influence of the electrostatic field, which is associated with the varying magnetic field, has an initial path of such radius as to obviate the difficulties hereinbefore mentioned.

The structure there shown comprises a highly evacuated toroidal tube 17 having the electron-emitting element 4 disposed immediately adjacent the inner periphery thereof and the target 6 disposed diametrically opposite, and adjacent to, the outer periphery thereof. A laminated iron core member 18, similar to that employed in transformers of the well known shell type, is built around the envelope 17 in such manner that the same is linked by two magnetic circuits 19 and 21 having a portion 22 in common, as indicated by the arrows of Fig. 5. The common portion 22 of the two magnetic circuits 19 and 21 is encircled by a magnetizing winding 23 which may be associated with a source 24 of alternating current or condenser discharge by conductors 25 and 26.

Mounted above and below the container 17 are a series of segmentally-shaped guiding magnets 27 and 28. The several magnets are so disposed upon the opposing faces of the tube 17 as to produce transverse fields near the inner and outer walls of the tube in order to produce a strong crowding action upon the electrons within the same; that is to say, an effect which tends to deflect the electrons from the inner and outer walls and to maintain them in a circular path which is midway between the inner and the outer peripheries of the container. The conductor

7 joining the cathode 4 and the target 6 may or may not include an energy source 8.

When the filament 4 is energized, electrons are driven off, some of the same moving 5 toward the left in Fig. 4. The electrons are deflected from the inner and outer peripheries of the container by the action of the strong magnetic fields which exist there by reason of the presence of the magnets 27 and 10 28. Hence, electrons are caused to revolve around the control magnetizable core in a substantially circular path. The effect of the varying flux in the control core, during one half-cycle of the alternating current, is 15 to develop an accelerating potential, by transformer action, causing the electrons to increase in velocity, for reasons hereinbefore mentioned. As the electrons increase in velocity, the effect of the increasing centrifugal 20 forces causes them to penetrate farther and farther into the magnetic field adjacent to the outer periphery and, ultimately, to strike the anode 6 and produce X-rays.

For illustrative purposes, I will give a 25 practical example of the solution of certain design problems connected with my invention, although it is to be understood that my invention is not necessarily limited to any particular design. Assuming that the highest 30 vacuum that can be maintained is 10^{-7} mm. of mercury, the mean free path of an electron, which it will travel before striking a molecule, will be approximately 35 500,000 cm. If an electron velocity corresponding to 100,000 volt potential is desired,

a voltage-gradient of $\frac{1}{5}$ volts per cm. is necessary for optimum operating conditions.

If D is the diameter of the circular path 40 traversed by an electron, and $\frac{1}{4}D^2$ is the cross-sectional area of the magnetizable core extending therethrough, the maximum 45 total flux is

$$\Phi = \frac{1}{4}D^2B,$$

where B is the flux density in the core. The 50 volts per turn are

$$10^{-8} \times 2\pi f\Phi = \frac{1}{2} \times 10^{-8} \pi f D^2 B,$$

and, since the length of a turn is πD , the 55 volts per cm. are

$$\frac{1}{2} \times 10^{-8} f D B.$$

Assuming a flux density of $B=10,000$ and a 60 frequency of $f=60$, the volts per cm. are

$$3 \times 10^{-8} D. \quad \text{To obtain } \frac{1}{5} \text{ volts per cm.,}$$

$D=70$ cm., approximately. If a frequency of 65 $f=600$ cycles per second were employed, the

diameter of the mean path of the electrons would be $D=7$ cm., approximately.

While I have shown my invention embodied in two different constructions, it is apparent that it is not to be limited thereby, 70 and that the broad principle, which has been illustrated, may be embodied in a number of applications involving greatly modified structure without departing from the spirit of my invention. I desire, therefore, 75 that only such limitations shall be imposed thereon as are specifically demanded by the prior art or indicated by the appended claims.

I claim as my invention:

1. The method of increasing the energy of an electron which consists in subjecting said electron to the influence of a varying magnetic field of sufficient magnitude to cause said electron to move in a path comprising 80 repetitions approximately like whorls, the energy of said electron increasing with each traverse of a repetition.

2. The method of increasing the energy of an electron which consists in subjecting said electron to the influence of an electric field and a varying magnetic field, the rate of change of said magnetic field being sufficient to cause said electron to move in a path comprising 90 repetitions approximately 95 like whorls, the plane of said path coinciding with that of said electric field, whereby the velocity of said electron will increase with each traverse of one of said repetitions in said path.

3. The method of increasing the velocity of an electron which consists in subjecting it to the influence of an electric field and of a varying magnetic field of sufficient magnitude and rate of change to cause the electron to traverse a spiral path, the direction of said magnetic field being such that the plane of said path will coincide with that of said electric field, whereby the velocity of said electron will increase with increased 105 length of said spiral and will correspond to a potential exceeding that producing said electric field.

4. An electron tube having a source of electrons and an electrode, said source and said electrode constituting the limits of the electron path and means for establishing a varying magnetic field across said path of an average intensity sufficient to prevent the electrons traveling the whole length of 115 said path in a single whorl and of a rate of variation sufficient to increase by a substantial amount the magnitude of the impact of the electrons against said electrode.

5. An electron-tube device including a 120 source of electrons, means for causing said electrons to move in nearly closed paths and means for causing the velocities of said electrons to increase throughout the lengths of 125 said paths.

6. An electron tube in combination with means for causing the electrons to move in a flat spiral path of more than one whorl.
7. An electron tube comprising a source of electrons, means for establishing a varying magnetic field in the vicinity thereof of sufficient intensity and sufficient rate of variation to cause said electrons to traverse paths of increasingly larger diameters embracing a portion of said varying magnetic field.
8. An electron-tube device comprising an evacuated toroidal envelope, a source of electron emission disposed adjacent the inner periphery of said envelope, an anode disposed adjacent the outer periphery of said envelope and means for establishing a varying magnetic field so disposed as to link said envelope.
9. An electron-tube device comprising an annular-shape envelope, an electron-emitting element disposed adjacent to the inner periphery thereof, a second element disposed adjacent to the outer periphery thereof, means for establishing forces in said tube tending to constrain electrons to a closed path extending around the annulus within the envelope and means for developing an accelerating force acting upon said electrons moving in said path.
10. An X-ray tube having an electron-emitting element and a co-operating element, means for producing a field of force between said elements and means acting throughout substantially the whole travel of the electrons for increasing the kinetic energy of the electrons emitted from said electron-emitting element to values higher than that produced by said field of force.
11. An electron tube comprising an annular shaped envelope having an electron-emitting element and a co-operating element suitably disposed therein and means for establishing a varying magnetic field so disposed as to link said envelope.
12. An electron tube comprising an annular-shape envelope having an electron-emitting element and a co-operating anode suitably disposed therein, means establishing forces in said tube tending to drive electrons circumferentially around said tube and means for establishing strong magnetic fields adjacent the inner and outer circumferences of said envelope tending to maintain the orbits of said electrons substantially circular.
13. An electron tube comprising an annular-shape envelope having opposite faces, an electron-emitting element and a co-operating element suitably disposed therein, means establishing forces in said tube tending to drive electrons emitted from said element circumferentially around said tube and guiding magnets so disposed upon the opposite faces of said envelope as to establish strong magnetic fields adjacent the inner and outer peripheries of said envelope tending to maintain the orbits of said electrons substantially circular.
14. An electron-tube device comprising a toroidal envelope, an electron-emitting element and a co-operating element suitably disposed therein, a magnetizable member adapted to form a magnetic circuit linking said envelope, means for energizing said member and means for establishing magnetic fields transverse to the plane of said envelope adjacent the inner and the outer peripheries thereof, said fields being such that electrons are repulsed when tending to enter the same.
15. An electron-tube device comprising a toroidal envelope, an electron-emitting element disposed adjacent the inner periphery thereof, a co-operating element disposed adjacent to the outer periphery thereof, a magnetizable member adapted to form a magnetic circuit linking said envelope, means for variably energizing said member, and guiding magnets so disposed as to establish a magnetic field transverse to the plane of said envelope adjacent to the inner and the outer peripheries thereof, said fields being such that repulsive forces are exerted upon electrons tending to enter the same.
16. An electron-tube device comprising an evacuated envelope, a source of electrons therein spaced from the outer periphery thereof, means for developing forces tending to cause said electrons to traverse closed paths, comprising repetitions approximately like whorls, the energy of said electron increasing with each traverse of a repetition, an anode within said envelope substantially outside of said paths, and means for producing a varying flux linking said paths and varying in such direction as to impress an accelerating potential upon said electrons, whereby said paths ultimately increase in diameter sufficiently for the electrons to impinge upon said anode.
17. An electron-tube device comprising an evacuated envelope, a source of electrons therein spaced from the outer periphery thereof, means for developing forces tending to cause said electrons to traverse an initial substantially circular path of predetermined diameter, an anode within said envelope substantially outside of said path, and means for producing a varying flux linking said path and varying continuously in such direction as to impress accelerating potentials upon said electrons, whereby said path ultimately increases in diameter sufficiently for the electrons to impinge upon said anode, the continuous unidirectional variation in flux being continued at least for a period commensurate with the mean time required for an electron to travel from cathode to anode.

18. An electron-tube device comprising a substantially toroidal evacuated envelope, a source of electrons therein spaced from the outer wall thereof, magnetic means operative near the walls thereof for developing forces normally tending to restrict the movement of the electrons to paths near the center of the cross-sectional area of the evacuated space, an anode within said envelope 5 adjacent the outer wall thereof and outside of the normal electron-paths, and means for producing a varying flux linking said paths and varying in such direction as to impress an accelerating potential upon said electrons, whereby said paths ultimately increase in diameter sufficiently for the electrons to impinge upon said anode.
19. An electron-tube device comprising a substantially toroidal evacuated envelope, a source of electrons therein spaced from the outer wall thereof, magnetic means opera- 10
- 15
- 20

tive near the walls thereof for developing forces normally tending to restrict the movement of the electrons to paths near the center of the cross-sectional area of the evacuated space, an anode within said envelope adjacent the outer wall thereof and outside of the normal electron-paths, and means for producing an alternating magnetic flux linking said toroidal container, whereby, 25 during at least one half-cycle of said alternating flux, said electron-paths ultimately increase in diameter sufficiently for the electrons to impinge upon said anode, the half-period for said alternating flux being at 30 least large enough to be commensurate with the mean time required for an electron to travel from cathode to anode.

In testimony whereof, I have hereunto subscribed my name this 29th day of March, 40 1922.

JOSEPH SLEPIAN.
